Primary Examiner — Karen E Eldridge Powers(74) Attorney, Agent, or Firm — Irina Hass(57) CLAIM

The ornamental design for a brush, as shown and described.

DESCRIPTION

FIG. 1 is a perspective view showing the new design for a brush;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top thereof; and,

FIG. 7 is a bottom plan view thereof.

The portions of the brush in FIGS. 1-5 and 7 shown in broken lines are included to show features that form no part of the claimed design.

1 Claim, 7 Drawing Sheets(56)
